UNITED STATES PATENT OFFICE.

WILLIAM P. TUCKER, OF BROOKLYN, NEW YORK.

SANDING DEVICE.

1,205,823.

Specification of Letters Patent. Patented Nov. 21, 1916.

Application filed April 20, 1916. Serial No. 92,472.

To all whom it may concern:

Be it known that I, WILLIAM P. TUCKER, a citizen of the United States, residing at Flatbush, Brooklyn, in the county of Kings and State of New York, have invented new and useful Improvements in Sanding Devices, of which the following is a specification.

This invention relates to sanding or anti-skidding devices for automobiles or similar vehicles.

The principal object of the invention is to provide a device of the character mentioned which will satisfactorily permit of the distribution on to the surface of the roadway, 15 quantities of sand, fine gravel or other similar granular material having the natural qualities of sand; delivering the sand in proximity to the driving wheels of the automobile and in the normal path thereof so as 20 to permit the driving wheels to take effective driving purchase against the roadway and at the same time positively preventing the vehicle from skidding on slippery surfaces 25 of the roadway.

Another and essential object of the invention resides in the distribution of sand or a similar material, respectively at the side of the driving wheels so as to arrest the 30 tendency of the vehicle to skid in either direction. In this manner the frictional surfaces between the roadway and the driving wheels of the vehicle will possess maximum efficiency and the operation of retarding the 35 tendency to skid is thereby perfected.

With the above and other objects in view which will appear as the nature of the invention is better understood, the same consists in the improved construction and novel 40 arrangements of parts which will herein-after be fully described and particularly pointed out in the claim.

In the accompanying drawings, has been illustrated, a single and preferred form of 45 the invention, it being, however, understood that no limitations are necessarily made to the precise structural details therein exhibited, but that changes, alterations and modifications within the scope of the claim 50 may be resorted to when desired.

In the drawings:—Figure 1, is a bottom plan view of a portion of an automobile showing the application of the invention thereto, the distributing valves being shown 55 in closed positions. Fig. 2 is a vertical section through a portion of the floor of a ve-

hicle showing the application of the invention thereto. Fig. 3 is a perspective view of a section of the valve plate.

I do not wish to limit myself to the specific location of the sand container upon the vehicle and it is desired that it be understood that the arrangement herein illustrated is only illustrative of one way whereby sand or like material may be temporarily 60 stored and carried upon the vehicle. It is stated, however, that I do not wish to arrange the sand container so that the sand may have an uninterrupted flow by its own gravity to the discharge or distributing 65 pipes to be hereinafter referred to.

The device consists of one or a plurality of 70 hoppers or containers 1—1, fixedly mounted upon the under side of the frame of the vehicle, the latter being conventionally shown 75 in dotted lines in Fig. 1. These hoppers have their large upper ends disposed in vertical alignment with openings formed in the floor (A), of the vehicle and it is preferred that the floor be provided with a removable 80 section (B), which may be closed over the upper ends of the hoppers normally. This arrangement permits the operator to readily fill the hoppers with sand as the occasion necessitates.

Each hopper is provided with a distributing pipe 2, and an outer distributing pipe 3, the upper ends of which being arranged to open into the hoppers as illustrated in Fig. 2. A valve mechanism 4, is 90 employed for the purpose of normally closing the pipes 2 and 3, said mechanism consisting principally of a plate 5, having sections 6—6 working in the hoppers at the lower ends thereof. At one side the plate is 95 provided with a stop flange 7, adapted to abut against the hoppers as shown in Figs. 1 and 2 and thereby prevent the plate from being accidentally moved entirely from the hoppers when closing the distributing pipes 100 2 and 3.

The valve mechanism is controlled manually. The plate 5, has connection with a rod 8, which extends in a longitudinal direction under the frame of the vehicle and at its forward end, the rod has pivotal connection at 9, with a rocking lever 10. This lever extends in an upward direction through the floor of the car and it is terminally arranged with such regard to the 105 operator's seat as to permit the operator to readily grasp and control the same at the 110

requisite time. The valve plate has its sections 6—6, formed each with a discharge slot 11, adapted to aline with the distributing pipes 2 and 3, when the rocking lever 10, is moved in one direction. At another time the portions 12, of the valve plate are adapted to close over the upper ends of the pipes 2 and 3, (see Fig. 2).

In carrying the invention into practice, 10 regard has been given the peculiar angular relation of the pipe 3, to the next adjacent pipe 2, of each hopper whereby when the valve mechanism is controlled for the purpose of discharging the sand on to the roadway, the sand will come from the discharge pipes in a continuous stream or film-like fashion at points respectively at the opposite sides of the driving wheels of the vehicle. This gives an uninterrupted or continuous friction surface between the driving wheels and the natural or slippery surfaces of the roadway. The result which follows this stated arrangement of the distributing pipes is such that the skidding of the vehicle is retarded almost instantly. The sand is distributed in the same manner against both of the driving wheels. The outer pipe

3, extends over and beyond the tread of the driving wheel and at a point in spaced relation thereto at the front side thereof. The inner pipe 2, is arranged substantially in converging relation to the outer pipe and it extends outwardly and slightly rearwardly as shown both in Figs. 1 and 2.

What is claimed as new is:—

A sanding device for automobiles comprising a sand container, a sliding valve therefor and a plurality of tubes normally closed by the valve and adapted to be simultaneously opened, the said tubes having their discharge ends disposed at the opposite sides of the path of movement of the automobile wheel, one of the said tubes being directed to discharge the sand, at the point of traction between the wheel and the ground and the other tube being directed to discharge the sand at one side and in advance of the said point of traction.

In testimony whereof I, affix my signature in presence of two witnesses.

WILLIAM P. TUCKER.
